(57) CLAIM

The ornamental design for an article locator with mini torch, as shown and described.

DESCRIPTION

FIG. 1 is a front perspective view of an article locator with mini torch, showing my new design;

FIG. 2 is a rear perspective view thereof;

FIG. 3 is a front view thereof;

FIG. 4 is a rear view thereof;

FIG. 5 is a top view thereof;

FIG. 6 is a right side view thereof; the left side view is a mirror image of the right side view, and is thus omitted; and, FIG. 7 is a bottom view thereof.

The broken lines in FIGS. 1 to 7 are for illustrative purposes only and form no part of the claimed design.
